(57) CLAIM

The ornamental design for a document holder, as shown and described.

DESCRIPTION

FIG. 1 is a perspective view of the document holder in a first position;

FIG. 2 is a perspective view of the document holder in a second position;

FIG. 3 is a front elevation of the document holder;

FIG. 4 is a rear elevation of the document holder;

FIG. 5 is a left side elevation of the document holder;

FIG. 6 is a right side elevation of the document holder;

FIG. 7 is a top plan view of the document holder; and,

FIG. 8 is a bottom plan view of the document holder.

The elements depicted by dashed lines in the drawing figures are for illustration purposes only and form no part of the invention.
